UNITED STATES PATENT OFFICE

HERMAN PAINES AND JOSEPH J. READLE, OF MUNCIE, INDIANA

VENTILATOR DEVICE

Application filed April 15, 1929. Serial No. 355,318.

This invention relates to improvements in ventilator devices intended to be used at the windows of dwelling houses, offices and factories.

5 Objects of the invention are to provide a device of this kind which while affording improved ventilation, will be effective to prevent the entry of snow or rain; will serve as a shade to intercept the outside rays of light, 10 and will also serve as a deflector of insects, dust and foreign particles.

Further objects of the invention are to provide a device of the kind described which is strong and durable, is economical of manufacture, and is capable of being easily installed, and of being kept in clean and sanitary condition.

The purposes of our invention are accomplished by and the invention is embodied in 20 the new construction, combination and arrangement of parts described in the following specification and defined in the appended claims. The invention is illustrated in the accompanying drawings.

25 Figure 1 is a front view of our improved ventilator device as it appears in position installed in a window casement of standard form, portions thereof being broken away.

Figure 2 is a top plan view taken on the 30 line 2—2 in Figure 1.

Figure 3 is a rear view of Figure 1.

Figure 4 is a side view taken on the line 4—4, as seen in direction of arrow 4 in Figure 1.

35 Figure 5 is an enlarged vertical sectional view taken on the line 5—5, and as seen in the direction indicated by arrow 4 in Figure 1.

Figure 6 is a detached detail view of the connection of the end of the cross bar to the 40 lower end of the flange of the side member, and the flashing plate being in position extended to the face of the window casement.

Figure 7 is a plan view of the formal metal sheet which constitutes one of the sides of 45 the ventilator device, and a stay for the frame members thereof.

Figure 8 is a front view of one of the cross bars.

50 Figure 9 is a front view of one of the glass panels.

Broadly stated, our invention consists of a rectangular frame, opposed sheet metal side plates having their rear edge portions in-turned and secured to the side members of the frame, and each having integral triangular body portions one above the other, the diagonal edges of which body portions are in-turned to constitute flanges, cross bars having their ends secured to the lower ends of the said flanges and being provided with internal lugs, glass panes having their lower edges in engagement with the said lugs and having their ends to register underneath the said flanges, and devices to hold the panes removably in their positions.

A ventilator device constructed in accordance with our invention, as shown in the drawings is especially adapted for use in a window of standard form. Upon the top portion of the frame there is provided a forwardly projecting and downwardly inclined apron plate, and a rearwardly projecting and upwardly inclined flashing member. The apron plate serves as a shelter above the uppermost pane, and the flashing member constitutes a closure between the top of the ventilator frame, and the bottom face of the upper sash of the window casement.

The frame of our improved ventilator device consists of the wooden side pieces 1 and 2, the top piece 3, and bottom piece 4, suitably connected together in the rectangular formation shown, and which said frame in the present instance is about thirty-six inches in width.

Each of the side members of our device consists of a sheet metal plate of about number twenty gauge, made up in blank formation as shown in Figure 7, and embodying three triangular body portions 5. The diagonal edge of each of said body portions is turned inwardly at an angle to constitute a flange 6, immediately below which is an ear 7. The vertical edge of each of said side members is turned at an angle to constitute a flange 8. Each end of said flanges 8 has a transversely extended integral body portion 9. Integral with each of said body portions 9 is an ear 10. A hole 11 in each of the flanges 10, the holes 12 in the transverse body por-

tions 9, and holes 13 in the flanges 8, permit of the use of screws or bolts for fastening the side members to the frame side pieces 1 and 2. The flanges 8 and the end portions 9 are secured in place by cap screws 14 and 16, the ears 10 are bent over and secured by cap screws 15. By this construction, the side members are suitably supported, and at the same time the wooden side and top pieces of the frame are strengthened, and their connections are braced.

The horizontal edges of the body portions 5 of the side members are of suitably ornate scalloped formation as shown. The function 15 of holes 17 in the flanges 6, and of holes 18 in the ears 7 will be presently referred to.

The cross bars 20, whose lower edges are scalloped, have their ends provided with holes 21 and 22 to register with holes 17 and 20 18 of the flanges 6 and ears 7 respectively, and they are secured thereat by small rivets. On the inner side of each of the said cross bars are secured small support clips 24. The glass panes 25, which are similar in length and 25 width, may be provided with the light metal top and bottom edging 26 and end strips 27. The said panes have their lower edges to rest on the support clips, and their ends to register immediately underneath the flanges 6, and 30 they are capable of being easily disposed in or removed from such position.

On a stud 28 that is provided in the inner face of each of the side members, is loosely retained a catch 29 of formation as shown in 35 Figure 5. This catch is provided with a foot portion 30 and the handle 31, and is of such form that when in the raised position, as shown, it holds the end of the glass pane securely in engagement with the underside of 40 the flange 6.

To permit of the removal of the glass pane, the catch is moved to the dotted line position. The sheet metal side members are at a suitable distance from the edges of the frame 45 pieces 1 and 2, so that the frame may be suitably modified in width to fit the casement in which it is to be installed.

A plate 32, with scalloped bottom edge, has its upper flange-like edge secured to the 50 top of the ventilator frame, and its body portion is inclined forwardly and downwardly. This is designated as an apron plate and it constitutes a shelter or shield above the adjacent glass pane.

To constitute a closure between the top of the frame and the underside of the upper sash of the window, we provide a flashing member. This flashing member consists of similar complementary thin sheet metal 55 plates 33 and 34 which are of the formation in plan as shown in Figure 2. The unsecured portions of these plates are of convex formation in cross section, as shown in Figure 5, and in their upward urge against the underside of the upper sash, the closure of this

jointure is sufficiently weatherproof. Cap screws 35 which are passed through spaced slots 36 and 37 in the said plates, are adapted to retain said plates loosely in position. The slots are so disposed that these plates are 70 slidable upon one another in opposite directions, in such manner as to extend the full distance between the sides of the window casement. When adjusted to such extended positions they may be secured by driving the 75 screws 35 to tightened contact therewith.

Projecting from surfaces of the rear side of the ventilator frame are spaced studs, upon which a screen frame 40 having the wire netting 41, is disposed. By wing nuts 42 this 80 screen frame is retained removably in connection with the ventilator frame. A handle 43, and latches 44, may be carried either by the ventilator frame, or by the screen frame. On the bottom piece 4 of the ventilator frame, a 85 felt strip 45 may be provided.

A ventilator device constructed in accordance with our invention is economical of manufacture, and it may be handled economically in transportation. The several parts may be 90 dimensioned for window casements of varied kinds and widths, and they are capable of being assembled and combined together into completed form, by a person of only ordinary skill.

Our improved ventilator device may be secured in position by the use of screws applied through the side pieces of the frame and driven into the window casement, or by the use of suitable clips or plates (not shown) 100 attached to the casement and with edges to overlap the edges of the ventilator frame side pieces.

Attachments of the preferred form, consist of hinges 47 which are secured to one of 105 the side pieces of the ventilator frame.

To place our improved ventilator device in use it is disposed in position in the window casement A, B, as shown in Figure 1, the closure plates 33 and 34 being in direct engagement with the underside of the upper sash C, and the butts of the hinges 47 being secured to the said casement. The panes 25 may be placed in position either before or after the 110 device is installed in place.

To hold the ventilator device in the position shown, the latches 44 are moved into engagement with the adjacent stop strip E of the window casement.

If it may be desired that the flashing member shall span the entire distance between the opposed faces of the window casements A and B, a transverse slit F (see Figure 6) is cut in each stop strip E, and E' at suitable predetermined height.

For the purpose of cleansing, or for replacement of any of the panes, the catch 29 is moved to the dotted line position; the pane is lifted clear of the lugs and it may then be conveniently lowered and removed. The 130

screen frame being removable, as hereinbefore described, the catches 29 are accessible from the interior of the window casement. Thus it is possible to easily keep the panes clean; and moreover, in case of breakage of any of the panes the replacement or renewal of same is of relatively small inconvenience. Also the screen frame is capable of being easily removed for cleaning, renewal, or repairs.

Our improved ventilator device is durable, relatively light in weight, and neat in appearance, and while being effective in an intercepting of the outside rays of light, there is a deflection of insects, dust and foreign particles, and facility for the free ingress or egress of air.

Modifications within the scope of the invention as defined by the appended claims, may be made.

What we claim as our invention, and desire to secure by Letters Patent, is:—

1. A ventilator device comprising a rectangular frame, opposed side plates secured to the members of the frame and each having triangular body portions one above the other, the diagonal edges of which said body portions are inturned to constitute flanges, cross bars having their ends secured to the lower portions of said flanges and being provided with internal lugs, panes to rest on said lugs, and having their ends to register underneath said flanges, devices to hold the panes removably in position, an apron plate above the top portion of the upper pane, a flashing extending rearwardly from the top of the frame, and latching means carried by the frame whereby to hold the frame in the window casement.

2. A ventilator device comprising a rectangular frame adapted to be reposed in the outer portion of the window casement, an awning device carried by the frame, a forwardly extending apron plate on top of the frame, and a rearwardly extended upwardly inclined resilient flashing plate secured to the top of the said frame.

3. A ventilator device comprising a rectangular frame adapted to be reposed in the outer portion of the window casement, an awning device carried by the frame, a rearwardly extended upwardly inclined flashing plate of resilient metal secured to the top of the frame, and latching means carried by the frame whereby to hold it in the window casement.

4. A ventilator device of the kind described, comprising a rectangular frame adapted to be reposed in the window casement, opposed side plates secured to the side members of the frame and each having triangular body portions one above the other, the diagonal edges of which said body portions are inturned to constitute flanges, cross bars having their ends secured to the lower

portions of said flanges and being provided with internal lugs, panes to rest on said lugs and having their ends to register underneath said flanges, devices to hold the panes removably in position, a forwardly disposed apron plate above the top portion of the upper pane, a resilient flashing plate secured to the top of the frame and disposed upwardly to make contact with the underside of the upper sash of the casement, a screen removably secured to the rear side of the rectangular frame, and latching means carried by the frame, and operable to hold the frame in the window casement.

In testimony whereof we affix our signatures.

HERMAN PAYNE.
JOSEPH J. READLE.
